[57] **CLAIM**

The ornamental design for a lid for box containing electrical filter, as shown and described.

DESCRIPTION

FIG. 1 is a first front perspective view of the lid of the present invention, engaged with an exemplary box for containing electrical filter, which is shown in broken lines;

FIG. 2 is a front view;

FIG. 3 is a side view;

FIG. 4 is another side view opposite of that shown in FIG. 3;

FIG. 5 is a rear view;

FIG. 6 is a top plan view; and,

FIG. 7 is a bottom plan view.

The box shown in broken lines is for illustrative purposes only and forms no part of the claimed design.
